(57) CLAIM

The ornamental design for a bowl set with wooden stand as shown and described.

DESCRIPTION

The patent or application file contains at least one drawing executed in color. Copies of this patent or patent application publication with color drawing(s) will be provided by the Office upon request and payment of the necessary fee.

1. Bowl set with wooden stand

Fig. 1.1 is a front view of a bowl set with wooden stand in accordance with the present design.

FIG. 1.2 is a back view thereof;

FIG. 1.3 is a left view thereof;

FIG. 1.4 is a right view thereof;

FIG. 1.5 is a top view thereof;

FIG. 1.6 is a bottom view thereof; and

FIG. 1.7 is a front left perspective view thereof.

The bowl set with wooden stand can be balanced or tilted by direction adjustment.
